UNITED STATES PATENT OFFICE.

JOHN McGREW, OF RAVENSWOOD, WEST VIRGINIA.

IMPROVEMENT IN MACHINES FOR CUTTING HOOP-LOCKS.

Specification forming part of Letters Patent No. 139,594, dated June 3, 1873; application filed February 19, 1873.

To all whom it may concern:

Be it known that I, JOHN McGREW, of Ravenswood, in the county of Jackson and State of West Virginia, have invented a new Improvement in Machines for Cutting Hoop-Locks; and I do hereby declare the following to be a full, clear, and exact description of the same, reference being had to the accompanying drawing forming a part of this specification.

The invention consists in the improvement of machines for cutting hoop-locks, substantially as hereinafter fully described and pointed out in the claims.

Figure 1 is a side elevation. Fig. 2 is a vertical section in line *xx* of Fig. 1. Fig. 3 is a horizontal section, and Fig. 4 is a detail view of the gage.

A is the table which supports the working-parts of machine; *B*, a raised platform screwed down thereto; and *C* uprights, with the detachable cap *C'*. The latter allows the tool-holder to be easily inserted or removed at any time. In these uprights are grooves or ways *c c*, in which slide the tongues *d d* of tool-holder *D*. The latter is notched on the inside at *d'*, so as to receive the bent double shanks *e e* of the obliquely-arranged cutters or knives *E*. The shanks may be made of the same length and slotted so as to be adjusted above one another and also to project successively at a greater distance out, thus enabling each to shave off a part only of the wood which is necessary to be taken out to form the notch; or, as shown in the drawing, these shanks *e* may be made larger for each successive upper knife. By constructing the knives with these bent shanks they can be firmly supported in the grooves of holder, and yet easily removed and replaced. *F* is a gage having the notch *f* obliqued and shaped to correspond to the cutters. This gage rests against a spring, *f'*, and is slid back thereagainst and under

the platform *B* by the inclines *G G*, which are attached to the sides of the movable tool-holder *D*. *H* is a lever pivoted to the frame at one end, resting on a spring, *h*, on the lower side, near the middle, and attached near the same point on the upper side, by a link, *h'*, to the tool-holder *D*.

By this construction and arrangement of parts the machine is enabled to operate as follows: The hoop rests against platform *B* in a suitable groove, *b*, thereof, and on the notched gage *F*. As the knives come down the first cuts out an angular shaving, when the inclines cause the gage to recede a little, and then stop to allow an additional one to be cut by the next knife. Again, the same operation takes place when the hoop is notched at one end. The opposite side of the other end being notched in the same way, the hoop-lock is formed.

This machine has been practically tested and is found to work with great facility, rapidity, and uniformity, and its parts subject to wear or accident are also easily taken out, repaired, and replaced, or new ones substituted.

Having thus described my invention, what I claim as new, and desire to secure by Letters Patent, is—

1. The series of vertically-reciprocating knives *E*, combined with an intermittently and horizontally moving gage, *F*, as and for the purpose set forth.

2. The arrangement of the inclines on reciprocating knife-holder, so as to operate the sliding gage in the manner described.

The above specification of my invention signed by me this 14th day of February, A. D. 1873.

JOHN McGREW.
